GEORGE L. VAN DINTER, OF MISHAWAKA, INDIANA, ASSIGNOR TO MISHAWAKA RUBBER AND WOOLEN MANUFACTURING COMPANY, OF MISHAWAKA, INDIANA, A CORPORATION OF INDIANA

FORM-FITTING-BOOT CONSTRUCTION

Application filed December 12, 1927. Serial No. 239,385.

My invention relates to footwear of the high top type commonly known as boots, and has reference more particularly to the construction thereof with a permanently closed 5 form fitting angle and instep portion which may be enlarged to facilitate putting on and removing the boot.

High top boots and especially those of rubber are usually made large and loose fitting 10 at the angle and instep to permit inserting and removing the foot, as it is quite difficult to make a boot of this character with a satisfactory expansible angle and instep portion which will stand the required usage without 15 developing leaks. It is desirable however to make the boot in a close fitting form, not only for the sake of improved appearance, but also to hold the boot securely in place and avoid the discomfort of the foot working up and 20 down in the boot. With my invention this is accomplished, and an expansible ankle and instep construction provided, which will remain waterproof throughout the life of the boot.

25 The principal objects of my invention are to provide an improved form fitting boot; to insure a substantial and effective waterproof construction at the angle and instep which permits enlargement at this point for applying and removing the boot; to construct the ankle and instep portion of the boot with an expansible pouch-like closure having flaps with a detachable connection for fitting the boot around the ankle and instep; to utilize 30 a special form of closing member at the ankle and instep, which folds into a compact and comfortable form and permits enlargement without stretching or other strains which might impair its water resisting character; 35 to provide an improved method of building an expansible waterproof structure into the boot; and in general, to provide a neat, attractive and substantial form fitting boot of simple construction.

40 On the drawings:

Fig. 1 is a perspective view of a boot embodying my improvements;

Fig. 2 is a perspective view showing the 45 manner of building up the boot on the last

or form, the upper portion of the last and boot structure being broken away;

Fig. 3 is an enlarged sectional view of the closed front of the boot, taken substantially on the line 3—3 of Fig. 1, but showing parts 55 lifted away from their usual close fitting position to more clearly disclose the construction;

Fig. 4 is a plan view of one of the half sections or quarters of the boot lining having the upper part broken away;

Fig. 5 is a front view of the expansible closing member partially assembled and with a portion broken away to disclose details of the construction;

Fig. 6 is a sectional view on the line 6—6 65 of Fig. 5;

Fig. 7 is a plan view of one of the front halves of the expansible closing member.

Fig. 8 is a plan view of the cap which is employed to reinforce the connections at the 70 lower end of the expansible instep portion;

Fig. 9 is a fragmentary front view showing the initial step in assembling the boot lining and expansible instep closure; and

Fig. 10 is a similar view showing a subsequent step in the assembling of the expansible instep closing parts.

75 Referring to the drawings, which show my invention applied to a boot of knee length, although it is of course intended for use with 80 boots of other lengths, the reference numeral 1 indicates the boot as a whole which is divided along the line 2 over the ankle and instep to form a pair of separable flaps 3 and 4, which are detachably connected in the 85 closed form fitting position by buckles 5 of a well known form or these flaps may be connected with any other suitable type of fastening devices. The flaps 3 and 4 are flared at their lower ends as indicated at 6 and 7 90 respectively, forming a "blucher" type of opening, and the vamp of the boot is provided with an extension 8 running up to and secured to the front wall of the boot at the upper end of the opening 2, said extension being provided at each side with inturned flaps 9 and 10 respectively, which are secured along their outer edges to the corresponding edges of the vamp extension 8. The inner edges of these flaps 9 and 10 are secured 95 100

respectively to the inner edges of the boot flaps 3 and 4. The vamp extension 8 and side flaps 9 and 10 thus form, in effect, an elongated pouch, which is slit down the front, and when the inner edges of the pouch flaps 9 and 10 are secured to the inner edges of the boot flaps 3 and 4, forms an expandible closing member which seals the opening afforded by the separable boot flaps 3 and 4, and at the same time permits separation of the boot flaps 3 and 4 and enlargement of the boot at the ankle and the instep for inserting and removing the foot.

As a further means of affording a close fitting of a boot of the knee length type, the latter may be provided at the upper end with a slit 11 and a strap and buckle fastener 12, or other suitable fastener for detachably connecting the portions of the upper at opposite sides of the slit 11, and the edges of the upper at opposite sides of the slit 11 are connected by a gore 13, which permits any desired expansion of the upper and folds down flat against the leg when the portions at opposite sides of the slit 11 are connected together.

While this construction may be used for any type of boot, it is particularly useful in connection with rubber boots, as it affords an expandible ankle and instep portion which will stand up under conditions of use to which rubber boots are subjected, without developing leaks which would impair the usefulness of the boot.

In making up a rubber boot with this ankle and instep construction, I prefer to proceed in the following manner: A pair of similar half sections of lining or quarters 14 of the form shown in Fig. 4 (which however has the upper portion broken away) are prepared and have the edges 15 of the toe portion secured together by a tape 16 or in other convenient manner. A vamp extension 8 of rubber composition, which forms the back wall of the pouch or closing member, is prepared in substantially the form shown in Fig. 5, and has a lining 17 of fabric adhesively secured to the back thereof, said lining being of somewhat smaller size than the vamp extension 8 to leave a marginal edge 18 of the vamp extension 8 exposed on the under side. A pair of side flaps 9 and 10 of rubber composition with fabric facing 19 (see Fig. 6) are then laid over the vamp section 8 or back member of the pouch or closing member, and have their marginal edges turned in under and secured to a marginal edge of the vamp extension 8 as indicated in Fig. 6, said flaps 9 and 10 being arranged so that they meet substantially along the longitudinal axis of the vamp extension 8, and these flaps 9 and 10 have their lower ends reversely flared as indicated at 20 and 21 respectively to correspond to the blucher form

or flaring arrangement 6 and 7 of the boot flaps 3 and 4.

After the pouch-like closing member has been prepared in this manner, the rounded lower end thereof between the points $x-x$ in Fig. 5 is laid over and secured to the upper end of the joined together toe portions of the lining 14-14 as shown in Fig. 9, so that the points $x-x$ of the closing member register with the points $y-y$ of the assembled lining, whereupon the edge portions of the two parts of the lining from the point y to approximately the point z of Fig. 4 are laid over and secured to the edges of the respective flaps 9 and 10. The forward edges of the two lining sections 14-14 at the upper end of the closing member and therebeyond to the top of the boot are then arranged edge to edge and secured together by a tape 22, and the pouch-like closing member is also temporarily closed by bringing the edges of the lining section 14-14 and with them the edges of the pouch flaps 9 and 10 together, as shown in Fig. 2 and applying a tape 23 across the meeting edges.

For reinforcing and insuring a thorough sealing of the connections between the various parts at the lower end of the closing member, a cap 24 of rubber composition of substantially the form shown in Fig. 8 is applied as shown in Fig. 2, so that it extends well down below and above the juncture line of the vamp portion of the lining sections 14-14 and the vamp extension 8, while the side lobes 25 of the cap 24 are folded over the lower ends of the side flaps 9 and 10 and the overlying portions of the lining around the points $x-y$, so that the corner connections of the flaps with the vamp portion of the shoe are well protected and thoroughly sealed against possibility of leakage.

After the lining and pocket closing member has been prepared, as above described, the assembled structure is stretched around a last 26, as indicated in Fig. 2, and the edges of the lining sections 14-14 are brought together at the back and secured together in any convenient manner, as by overlapping and cementing or taping. After the lining has been applied on the last, the sole is built up in the usual manner, and the facing 27 of rubber composition applied over the lining to complete the upper, said facing being preferably provided with a pointed portion which fits up between the curved lower ends 6 and 7 of the side flaps 3 and 4, as indicated by dotted lines at 28 in Fig. 1, and the facing on the side flaps 3 and 4 being continuous across the line of separation 2, so that the side flaps 3 and 4 are joined together by the facing, the line of division being preferably marked by a score line which terminates near the upper end of the pocket or closing member, while the side portions of the upper thereabove are

overlapped or provided with a reinforcing 29 extending up to the top of the boot.

After the boot has been assembled in this manner it is vulcanized, and after vulcanizing the facing 27 and the tape 23 are slit 5 along the line 2 up to the lower end of the reinforcing 29, so that the side flaps 3 and 4 may be separated to expand the ankle and instep portion of the boot for applying and 10 removing. The fasteners 5 may be attached in any convenient manner, preferably by means of tabs which are arranged in place before the boot is vulcanized, or any other desired type of fastener may be employed, 15 the essential requirement being the provision of the boot with a serviceable and thoroughly waterproof expandible portion at the ankle and instep which is sufficiently strong and durable to avoid the necessity of making rubber boots in a loose fitting form. 20

While I have shown and described my invention in a preferred form, I am aware that various changes and modifications may be made without departing from the principles 25 of my invention, the scope of which is to be determined by the appended claims.

I claim as my invention:

1. The method of making a boot with an expandible instep which comprises forming an 30 elongated pouch with a longitudinal slit in the front wall and a closed upper end, securing the quarters of the lining to the edges of the slit and to the closed upper end of the pouch, temporarily closing the slit, then applying the lining and pouch on a last, then securing facing material over the lining and across the closed slit and upwardly therefrom and then dividing the facing material and the temporary closure along the line of the 40 slit approximately to the upper end of the pouch and leaving an undivided portion of the facing therebeyond.

2. The method of making a boot with an expandible instep which comprises forming 45 an elongated pouch with a front and back wall, securing the boot lining to the front wall of the pouch so that the latter is spaced from the upper and lower ends of the lining, then applying the facing over the lining and 50 across the front wall of the pouch, and then slitting the facing and the front wall of the pouch midway between the lateral edges of the latter and terminating the slit below the upper end of the pouch.

3. The method of forming a boot with an expandible instep portion which comprises forming an elongated elliptical member and a pair of elongated semi-elliptical members, then securing the semi-elliptical members 55 respectively to the lateral edges of the elongated elliptical member so as to form a divided front wall over the elongated elliptical member, then securing the lining to the inner edges of the semi-elliptical members and 60 connecting said edges, then applying a fac-

ing over the lining and across the slit, and then slitting the facing and disconnecting the edges of the semi-elliptical members.

4. The method of making a boot with an expandible instep portion, which comprises 70 building an elongated laterally expandible pocket member onto the inner side of the front wall of the boot at the ankle and instep and below the top of the boot, then vulcanizing the pocket member in a closed position 75 between the front wall of the boot and a last, and then dividing the wall of the boot part way up the front longitudinally over and between the ends of the pocket member and leaving the front wall undivided there- 80 above.

5. The method of making a boot with an expandible instep portion which comprises 85 forming an expandible pocket of fabric reinforced rubber composition with an elongated back wall and overlying side flaps flared at their lower ends, and building the pocket onto the inner side of the front wall of a boot having a flaring formation overlying the flared lower ends of the side flaps of the pocket, and then vulcanizing the assembled structure on a last. 90

6. The method of making a form fitting rubber boot which consists in interposing between the front wall of the boot and a last, a pouch like member terminating below the top of the boot and consisting of a fabric reinforced back wall with inwardly extending side flaps of fabric reinforced rubber composition thereover and flared at their lower ends, then vulcanizing the assembled structure on the last, and then dividing the front wall along the line of separation of the pocket side flaps. 100

7. The method of making a form fitting boot which consists in assembling a pouch of rubber composition with side walls flared at their lower ends on the inner side of the front wall of a boot having a correspondingly flared portion, then applying a reinforcing of rubber composition at the outer extremities of the flared portions of the pocket and front wall of the boot, and then vulcanizing the assembled structure on a last. 105

8. The method of making a boot with an expandible portion at the ankle and instep, which comprises building an elongated laterally expandible pocket member of rubber composition onto the inner side of the rubber composition wall of the boot, then vulcanizing the pocket member in a closed position between the wall of the boot and a last, and then slitting the portion of the wall overlying the pocket member longitudinally of the boot and between the ends of the pocket member and leaving an unslitted portion of the boot wall beyond the upper end of the slit. 115

9. The method of making a rubber boot with an expandible instep portion which comprises vulcanizing a pocket member to the 120

under side of a portion of the boot wall remote from the upper end thereof, then slitting the boot wall portion over the pocket so that the upper end of the slit terminates at or below the upper end of the pocket.

10. The method of making a rubber boot with an expansible instep portion which comprises vulcanizing a central longitudinal portion of the front wall of an elongated pocket member to the under side of a portion of the front wall of the boot remote from the upper end thereof, then slitting the front wall of the boot along said central longitudinal portion of the pocket front wall so that 15 the upper end of the slit terminates at or below the upper end of the pocket.

11. The method of providing a rubber boot, having separable flaps of the blucher type spaced from the upper end of the boot and defining a transversely extending opening at the bottoms of the flaps, with an expansible instep portion, which comprises vulcanizing the front wall of an elongated pocket member having a closed top end and an open 25 bottom end to the under side of the instep portion of the boot wall and below the top of the boot, and vulcanizing the lower open end of the pocket member to the margin of the transversely extending opening in the 30 boot wall defined by the lower end portion of the flaps.

12. The method of making a rubber boot, having separable flaps of the blucher type spaced from the upper end of the boot and 35 defining a transversely extending opening at the bottoms of the flaps, with an expansible instep portion, which comprises building onto the under side of the separable blucher flaps of the boot wall a pocket member having its front wall divided along the line of separation of said flaps and having its lower end opening through the transversely extending opening in the boot wall at and defined by the lower ends of the flaps, vulcanizing 40 the assembled structure on a last, and then slitting the boot wall along the length of the pocket from the open lower end of the pocket to the upper end thereof.

13. The method of making a rubber boot 50 of the class described which comprises assembling a pocket member, which has a front wall with a pair of elongated flap portions joined together at the upper ends and flared at their lower ends, under a similar pair of 55 elongated instep flap portions of the boot wall, then vulcanizing the corresponding boot wall and pocket flaps together along their inner edges and permanently shaping the pocket and the said instep flap portions 60 of the boot wall in compact superposed nested relation and in corresponding transversely arched and longitudinally curved form.

14. The method of making a rubber boot 65 with an expansible instep portion which in-

cludes providing, on the underside of an instep portion of the boot wall remote from the upper end thereof, a pocket member with front and back rubber composition walls connected together at the sides and at the top of the pocket, then vulcanizing the assembled structure on a last, and then slitting the assembled structure at the front of and between the top and bottom ends of the pocket member to form separable flaps with an opening therebetween leading into the interior of the pocket member.
